Ezekiel Wolf.

ATTORNEY.

UNITED STATES PATENT OFFICE.

ROBERT LONGFELLOW WILLIAMS, OF NEWTON, MASSACHUSETTS, ASSIGNOR TO SUB-MARINE SIGNAL CORPORATION, OF BOSTON, MASSACHUSETTS, A CORPORATION OF DELAWARE.

SOUND-RECEIVING APPARATUS.

Application filed November 15, 1924. Serial No. 750,218.

The present invention relates to the reception of sound waves and more particularly to the reception of compressional waves in water or other similar medium in which the 5 sound or compressional waves act to operate an electric circuit either to open or to close the same.

In an embodiment described in this specification the circuit is broken by the action of 10 the incoming signal upon a diaphragm which, in its motion, opens an electrical contact between two conductive metals, preferably platinum sealed in a gas chamber filled with nitrogen to prevent oxidation of the contacts.

15 The object of the invention described in the present specification is to obtain an apparatus which will indicate by the opening of an electrical contact an incoming signal.

Another purpose of the present invention 20 is to have the incoming sound or compressional signal operate to break a current of considerable value either directly or indirectly by the action of the signal itself and thus may be useful for operating any kind of electrical mechanism without requiring amplification as is generally necessary when a microphone is used as a receiver.

It is also the purpose of this construction 25 to have such a device operate by the signal alone and not by stray sounds which come in contact with the device.

In the embodiment described below the hydrophonic relay as it may be called has a diaphragm mounted on a watertight case, 30 the diaphragm supporting an insulated electrical contact. A second electrical contact normally resting upon the first is mounted upon a pivoted balanced rod insulated as the first contact. When the incoming signal agitates the diaphragm the second contact is 35 thrown off by the first and the circuit is broken. Further objects of the present invention and details of construction will be learned from the description and drawing of 40 the specification, in which Figure 1 represents a cross sectional view of the apparatus. Figure 2 an enlarged view of the details of the contact mechanism and circuit, taken partly along line 2—2 of Figure 3. Figure 3 45 shows a plan view of Figure 2 and Figure 4 a detail of the pivot.

In Figure 1 the device shown is adapted 50 to pass through the cylindrical portion of a valve and have the diaphragm 1 exposed to the water or transmitting medium. The dia-

phragm has a heavy rim 3 threaded as shown in Figure 1 and by means of the spanner hole 36 is screwed on a cylindrical shell 5 forming a part of the wall of the receiving device. A rubber or other form of a watertight washer 60 38 is thereby squeezed between the abutting surfaces of the piece 5 and the rim 3 to form an airtight, as well as a watertight joint. A damping diaphragm 2 sets over the diaphragm 1 to make the diaphragm somewhat 65 aperiodic and prevent excessive motion.

In the center of the diaphragm is a boss 21 which is either a part of the metal of the diaphragm or a piece of metal spot welded to the diaphragm. A bakelite or other insulating bushing 22 is secured in this boss and a platinum point 23 is set in the bushing. Above the platinum point is a platinum stud 24 which sets firmly in a stud 25 threaded at the other end and adjustable in the pivoted 70 arm 18. A spindle 19 which passes through the arm 18 is pivoted in a jewel bearing 32 at both ends as indicated in Figure 3 and insulates the arm 18 from the lower platinum contact 23.

A conductor 35 is soldered or otherwise attached to the spindle 19 in the manner shown in Figure 2 to allow free motion of the spindle. A second conductor 20 of thin wire is connected to the platinum point 23. These 85 two wires are led to the indicating circuit which, in the present case, consists of the battery 28, the primary 29 of a transformer, and a secondary 30 in which the potential induced by breaking of the platinum contacts 90 23 and 24 operates an indicating mechanism, in the present illustration, an electric luminous discharge in a gaseous tube 31.

The spindle 19 is supported between the 95 prongs of the U shaped member 14 which rests upon an arm 18 integral with the shell 5 as shown in Figures 1 and 2. Machine screws 15 in the cross piece 17 of the support pass through an insulating bushing 16, thus insulating the pivoted arm 18 in event the 100 jewel bearing is not sufficient insulation.

The arm 18 has an adjustable weight 11 which may be positioned upon the arm in the place desired to obtain the proper balance so that the contact 23 and 24 will open under the 105 action of the incoming signal. The stud 25 is also adjustable in a vertical position to attain a proper balance.

A pin 27 secured in the piece 17 and bent at right angles over the end of the bar 18 pre- 110

vents the bar 18 from moving excessively out of the normal position and thereby prevents any strain upon the connection to the spindle 19 or the jewel bearing.

5 About the shell 5 is a soft rubber casing 4 which has a serving 34 to bind the rubber tightly in place. This rubber serves to act as a sound insulator and also to make a good fit in the cylindrical valve in which the device is 10 inserted. A stem 8 has a flange 6 at its lower end, through which machine screws 7 pass holding the shell 5 securely to the stem. A watertight and airtight gasket 39 of a suitable character is inserted between the pieces 15 6 and 5 to insure that the inner space is tightly sealed. The conducting leads pass through the stem which is sealed at the upper end by a suitable bushing as shown in Figure 1. There is provided a hole 9 in the stem 8 which 20 can be used for testing the device for leaks and which is sealed with a test plug when the testing is completed.

Since the leads 12 have some play in the stem 8 the hole 9 may be used to pump nitrogen into the space after the air has been pumped out.

As has been explained above, the present device may be adapted to be inserted in the skin of a vessel through a cylinder of a gate 30 valve. With this end in view the outer end of the receiver is constructed in a piston head fashion while the stem resembles a piston rod. However, this receiver may also be suspended in a water tank within a vessel or even 35 hung overboard as the conditions may demand.

The device which has been described above 40 usually operates in a position approximately that as shown in Figure 1. Due to the fact that the only means which hold the two platinum contacts together is the action of gravity on a balanced arm, this pivoted arm must normally be in an approximately horizontal position. It is conceivable that this condition 45 need not be specifically complied with as long as the action of gravity just holds the contacts together. The arm could possibly be of other shapes and still perform the above function properly.

50 The operation will be described briefly. The incoming signal acting upon the diaphragm causes the latter to vibrate. In the present case this vibration is somewhat damped so that it does not persist as long as a perfectly free vibration of a free diaphragm. The lower platinum contact will, however, vibrate somewhat. On the first vibration the platinum point 23 will move upwards, thereby throwing off and opening the contact with 55 the upper platinum stud 24, since the latter acts as a very light mass due to the careful adjustment of balance. For the same reason the upper stud will return somewhat slowly allowing the vibrations of the lower stud to 60 die down sufficiently so that the upper stud

will not be thrown off again unless the signal is continued.

There is a distinct advantage in the present type of receiver, especially where the signal is short as is usually the case in the measurement of distance by submarine signals and radio signals, or in the measurement of depth where a signal is emitted and the returning echo operates an indicator. Another advantage in the present device is that considerable current can be broken and, therefore, the signal is at the same time amplified.

Having now described my invention I claim:

1. In a system for receiving and indicating submarine sound signals, a submarine sound receiver comprising a water-tight casing, a diaphragm forming one side of said casing and adapted to be exposed in a substantially horizontal position to the water, 80 an electrode mounted within said casing substantially on the center of said diaphragm, an arm carrying near one end a second electrode adapted to make a light contact with said first electrode, and means for freely pivoting and balancing said arm substantially in a plane parallel to said diaphragm including a counter balance adjustable on said arm.

2. In a system for receiving and indicating 95 submarine sound signals, a submarine sound receiver comprising a watertight casing, a diaphragm forming one side of said casing, a soft rubber sheet covering substantially the entire inner surface of said diaphragm, said diaphragm being exposed in a substantially horizontal position to the water, an electrode mounted within said casing substantially on the center of said diaphragm, an arm carrying near one end a second electrode adapted 100 to make a light contact with said first electrode, and means for pivoting freely and balancing said arm substantially in a plane parallel to said diaphragm.

3. In a system for receiving and indicating 110 submarine sound signals, a submarine sound receiver comprising a watertight casing, a diaphragm forming one side of said casing and adapted to be exposed in a substantially horizontal position to the water, an electrode mounted within said casing substantially on the center of said diaphragm, an arm carrying near one end a second electrode adapted 115 to make a light contact with said first electrode, means for freely pivoting and balancing said arm substantially in a plane parallel to said diaphragm including a counter balance adjustable on said arm, and means for limiting the swing of said arm.

4. A system for receiving and indicating 125 submarine sound signals including an electrically energized circuit and a submarine sound receiver having a pair of contacts normally completing said electrical circuit, said submarine sound receiver comprising a 130

- watertight case, a diaphragm closing a part of said case, one of said contacts mounted directly on said diaphragm, means for pivoting the other of said contacts with freedom 5 of movement to and from said first contact including an arm on which said contact is mounted and a counter balance adjustable to such a position on said arm that the contacts make light contact with each other, an 10 inert gas filling the space within said casing, and means comprising in part said electrical circuit and including a step up transformer and a gaseous discharge indicator for rapidly 15 flashing said indicator upon the receipt of a sound.
5. A system for receiving and indicating submarine sound signals comprising a submarine sound receiver consisting of a watertight casing, a diaphragm forming a part of 20 said casing having a soft rubber sheet covering the inner surface thereof, a pair of contacts, means for mounting one of said contacts on said diaphragm, means for pivoting and balancing the other of said contacts 25 freely on said first contact including an arm on which said contact is mounted and a counter balance adjustable to such a position on said arm that the contacts make light contact with each other whereby the receipt 30 of a sound impulse will immediately open said contacts and an indicating circuit operated by the opening of said contacts for producing a momentary discharge across a gaseous tube comprising said gaseous tube, 35 a transformer operating the same, and an electrical circuit having a source of energy connecting said transformer and said contacts.
6. In a submarine sound receiver a diaphragm for receiving the sound waves, an electrode mounted substantially on the center of said diaphragm, an arm, adjustable 40 means for mounting a second electrode in said arm including a threaded stud on which said electrode is mounted, threading into 45 said arm, means for pivoting said arm to allow freedom of movement of said second electrode to and away from said first electrode and adjustable means for balancing said arm in a substantially horizontal position to provide only slight pressure between 50 said electrodes.
7. In a submarine sound receiver a diaphragm for receiving the sound waves, an electrode mounted substantially on the center of said diaphragm, an arm, adjustable 55 means for mounting a second electrode in said arm including a threaded stud on which said electrode is mounted, threading into said arm, means for pivoting said arm to 60 allow freedom of movement of said second electrode to and away from said first electrode and adjustable means for balancing said arm in a substantially horizontal position comprising a screw threaded portion 65 provided on said arm and a counter weight threading said screw threaded portion whereby the desired pressure between said electrodes may be obtained.
8. In a submarine sound receiver a diaphragm for receiving the sound waves, an electrode mounted substantially on the center of said diaphragm, a second electrode positioned normally in contact with said first electrode and directly bearing on the latter, an arm positioned substantially parallel to said diaphragm, means for mounting said second electrode in said arm, a forked support carried by the casing, means for pivoting said arm between the forks of said support to allow a free up and down movement of said arm, and means for adjusting the pressure exerted by the second electrode 70 on the first.

In testimony whereof I affix my signature.
ROBERT LONGFELLOW WILLIAMS.
